UNITED STATES PATENT OFFICE.

EDGAR LA RUE, OF DEVILS LAKE, NORTH DAKOTA.

DISPENSING APPARATUS FOR GREASE AND SIMILAR MATERIALS.

1,177,423.

Specification of Letters Patent. Patented Mar. 28, 1916.

Application filed December 31, 1914. Serial No. 879,918.

To all whom it may concern:

Be it known that I, EDGAR LA RUE, a citizen of the United States, residing at Devils Lake, in the county of Ramsey and State 5 of North Dakota, have invented certain new and useful Improvements in Dispensing Apparatus for Grease and Similar Materials, of which the following is a specification.

The present invention relates to improvements in apparatus designed to dispense oils, 10 greases, or similar viscous materials, and serving the purpose of what are now well known as "grease guns."

The object in view is to provide an apparatus of this type which will eliminate to 15 the greatest extent the necessity for handling the grease, saving incidentally the disagreeable work accompanying such process, as well as the time and labor ordinarily required in operating the type of grease gun 20 now in use.

To this end the apparatus consists of a supply reservoir in which the grease or oil is contained, a piston operable in the reservoir by pressure means, measuring means 25 for determining the amount of grease expelled therefrom, and finally a valve controlling the operation of the piston and dispensing of said grease. In this connection, 30 it may be mentioned that one of the advantageous features of my apparatus is its compactness which not only facilitates its manipulation or handling but enables its manufacture at a minimum cost. This and such 35 other objects as may hereinafter appear are attained by the novel construction, combination and arrangement of parts to be herein- 40 after specifically described and claimed.

Reference will now be had to the accompanying drawing forming a part of this specification, wherein:

Figure 1 is a sectional view through an apparatus constructed in accordance with my invention. Fig. 2 is a fragmentary plan 45 view of the housing for the measuring element forming a part of this invention. Fig. 3 is an enlarged sectional view of the upper portion of the apparatus showing more

clearly the details of construction; and Fig. 4 is a horizontal sectional view taken on 50 the plane indicated by the line 4—4 of Fig. 3.

Throughout the following detail description, and on the several figures of the drawings, similar parts are referred to by like 55 reference characters.

Referring to the drawing and describing my apparatus, the same consists of a supply tank or reservoir 1 which constitutes a cylinder and a piston 2 operable therein. The 60 reservoir is preferably provided with a removable bottom 3 which has threaded connection with the reservoir 1 as clearly shown in Fig. 1. Connected to the lower portion of the apparatus is a flexible dispensing 65 tube 4 by means of which the material, such as grease or oil contained by said reservoir may be supplied to a machine or part requiring said grease. The tube may be supplied in the usual manner with a nozzle (not 70 shown) and it is preferably provided with a valve 5 intermediate its length for controlling the passage of the material therethrough. In Fig. 1, it will be noted that the reservoir 1 is formed with an offstanding 75 clamping support 6 in which the tube is removably disposed whereby to normally maintain the said tube in elevated position away from the surface on which the apparatus may be disposed. 80

The piston 2 has supportingly connected thereto a flexible measuring tape 7, said tape being preferably metallic and provided with suitable indicia thereon whereby the quantity of material dispensed from the 85 apparatus may be easily determined. The tape is mounted upon a shaft 8 journaled in the sides of a housing 9 suitably secured to the top of the reservoir 1, said housing having a sight-window 10 therein, in order 90 that the indicia on said tape may be discernible as most clearly shown in Fig. 3.

The reference numeral 11 designates an air valve provided for the purpose of introducing air pressure into the receptacle 1 95 above the piston which piston is adapted to

be actuated so as to expel the grease or material in the receptacle beneath the same upon opening of the valve 5. A suitable air gage 12 is provided for registering the 5 pressure in the apparatus.

From the foregoing description, it will be obvious that it is only necessary to supply, for instance, an automobile differential with grease to introduce the nozzle of the 10 tube 4 into the differential housing and by opening the valve 5 allow the pressure above the piston 2 to act thereupon and force the material through said tube, the amount or quantity of the material thus supplied being 15 indicated by the metal tape 7 which is unwound from the shaft 8 by downward movement of the piston. When it is desired to refill the receptacle 1, it is only necessary to remove the bottom 3 and to insert the desired amount of grease. 20

The foregoing arrangement is extremely compact by reason of the utilization of a metal tape which occupies a minimum amount of space within the small housing 25 on top of the receptacle, and it very adequately performs the registering function for my special arrangement.

As is usually desired, locking means for rendering the apparatus inoperative may be 30 provided and in this instance it consists of the formation of the shaft 8 with an extension 8' projecting laterally from the housing 9 a desirable distance. The extension has its bearing in a bracket 13 secured to the 35 housing 9 and said bracket performs a dual function. This bracket 13 abuts with a shoulder 8" on the shaft extension adjacent to a suitable bushing 14, in said shaft, and acts to hold said shaft in proper position 40 in its bearings with a view to preventing any leakage of air pressure from the receptacle. In addition the bracket is provided with a passage 18' extending transversely of its outer bearing extremity and the extension 45 8' of the shaft is formed with an opening 15 therein which is adapted to register with the passage 18' so that a lock member 16 or other desirable means may be inserted therethrough for rendering the shaft inoperative. The lock aforesaid is conventionally shown as any locking means may be employed for this purpose of rendering the unauthorized use of the apparatus impracticable. The end of the shaft extension 8' is 55 squared as shown in the drawing so that a crank 17 or similar means may be connected thereto for rotating the shaft to wind up the metal tape and thereby raise the piston 2 when desired. 60 As will be observed particularly by reference to Fig. 3 of the drawing, the shaft 8 is disposed slightly to one side of the center of the receptacle so as to maintain the

metallic tape 7 in substantially a true vertical plane throughout the revolution of said 65 shaft in the movement of the piston 2.

It will be apparent that slight changes in the details of construction, and arrangement of the parts in this apparatus may be made without departing from the spirit of the invention, and within the scope of the appended claims. 70

Having thus described my invention, what I claim as new is:

1. In apparatus of the class described for dispensing grease or the like, the combination of a receptacle, a piston operable therein, means for introducing pressure into said receptacle for actuating the piston in one direction, a flexible indicating member connected to the piston and operable thereby for determining the quantity of material expelled from said receptacle, a shaft upon which the indicating member is wound and operable to cause movement of the piston by 85 the indicating member in the opposite direction to that incident to actuation by the pressure medium aforesaid, and a housing on the receptacle on which the shaft is journaled and inclosing the indicating member, 90 said housing having a sight opening for reading the indicating member.

2. In apparatus of the class described for dispensing grease or the like, the combination of a receptacle, a piston operable therein, means for introducing a pressure medium into said receptacle for actuating the piston, a flexible indicating member connected to the piston and operable thereby for determining the quantity of material expelled from said receptacle, a shaft upon which the indicating member is wound, means for retracting the piston and rewinding the indicating member, a housing for said indicating member disposed upon the 105 receptacle, the latter having an opening establishing communication between the receptacle and said housing and through which opening said indicating member passes, said housing having a sight opening 110 for reading the indicating member and being airtight to withstand pressure of the pressure medium in the receptacle.

3. In an apparatus of the class described for dispensing grease or the like, the combination with a reservoir, a piston operable therein, a shaft rotatably mounted on the reservoir, a flexible support member intermediate the shaft and piston and adapted to be wound upon said shaft and also unwound, bracket means preventing displacement of said shaft, and locking means for interlocking the shaft with the last-mentioned means to render the piston inoperative. 115

4. In an apparatus of the class described

for dispensing grease or the like, the combination with a reservoir, a piston operable therein, pressure means for moving the piston downwardly, a shaft journaled on said reservoir, a bracket coacting with the shaft to hold the same from displacement, said bracket forming a bearing for said shaft, said shaft and bracket having openings therein adapted upon registry to permit the insertion of a locking member, a supporting

member intermediate the shaft and the piston, and means for actuating said shaft to raise the piston.

In testimony whereof I affix my signature in presence of two witnesses.

EDGAR LA RUE.
